UNITED STATES PATENT OFFICE.

ERNEST C. STYBERG, OF RACINE, WISCONSIN.

DESIGN FOR A RECORDER FOR CARD GAMES.

Application filed February 16, 1925. Serial No. 12,389. Term of patent 3½ years.

To all whom it may concern:

Be it known that I, ERNEST C. STYBERG, a citizen of the United States, and a resident of Racine, in the county of Racine and State of Wisconsin, have invented a new, original, and ornamental Design for Recorder for Card Games, of which the following is a specification, reference being had to the accompanying drawing, forming part thereof.

Figure 1 is a front elevation of the recorder for card game, and Figure 2, is an end view of same.

I claim:

The ornamental design for a recorder for card games, as shown.

In testimony that I claim the foregoing I have hereunto set my hand at Milwaukee, in the county of Milwaukee and State of Wisconsin.

ERNEST C. STYBERG.
